RAILWAY TRUCK ANCHOR DEVICE

James C. Travilla, University City, and Richard L. Lich, St. Louis, Mo., assignors to General Steel Castings Corporation, Granite City, Ill., a corporation of Delaware

Application February 10, 1954, Serial No. 409,416

13 Claims. (Cl. 267—67)

The invention relates to railway rolling stock and more particularly to the connections between relatively movable railway truck parts, such as a truck frame and bolster, which should be held in predetermined spaced relation to each other lengthwise of the truck but have movements relative to each other transversely and vertically of the truck under conditions which require that the relative movement be controlled or limited in direction and extent. An anchoring device of the general type to which the present invention relates is illustrated in J. C. Travilla Patent No. 2,369,991, issued February 20, 1945.

It is an object of the present invention to connect the ends of an elongated anchor to the truck parts so that the anchor while serving as a strut or link to transmit buffing and draft forces between the truck parts will accommodate movement of the parts relative to each other transversely of the longitudinal axis of the anchor and, during such movement, develop controllable friction between associated elements and particularly between the truck parts and the anchor members, snubbing the relative movement of the truck parts. Such frictional snubbing action may be developed to an extent which will avoid the necessity of using shock absorbers or other snubbing devices between the interconnected truck parts as has been customary and it is a further object of the invention to simplify and reduce the cost of the truck structure accordingly.

In the accompanying drawings illustrating the invention:

Figure 1 is a side elevation of a railway four wheel truck in which the truck side frame and bolster are connected by an anchor embodying the present invention.

Figure 2 is a detailed top view and horizontal section of the anchor and associated truck frame and bolster structure shown in Figure 1 and drawn to an enlarged scale.

Figure 3 is a detailed section of one end of the anchor shown in Figure 2 with the anchor arm inclined from its normal position and the other parts shifted accordingly.

Figure 4 corresponds generally to Figure 3 but illustrates another form of the invention.

Figure 5 corresponds to Figure 4 but illustrates another form of the invention.

Figure 6 corresponds to Figures 4 and 5 but illustrates another form of the invention.

Figure 7 illustrates another form of the invention in which one end of the anchor is similar to the ends as shown in Figure 2, while the other end has the rubber pad and ball and socket in reverse location relative to the associated truck part flange.

The truck shown in Figures 1-3 comprises the usual wheels 1, axles 2, journal boxes 3, equalizers 4, equalizer springs 5, and a truck frame supported on springs 5, and comprising wheel pieces 6 with depending pedestal legs 7 and 8 slidably receiving between them journal boxes 3.

Hangers 9, suspended from the brackets 10 on each of

2

the truck frame wheel pieces, swing transversely of the truck and, at their lower ends, carry a cross bar 11 which supports one end of a spring plank 12 mounting upright coil springs 13 which support the load-carrying bolster B.

5 All of the above-mentioned parts are in general use and it will be understood that bolster springs 13 deflect vertically and transversely of the truck to yield to vertical shocks and to relatively small lateral shocks applied to the truck and bolster. Larger lateral shocks are accommodated by the swinging of hangers 9.

To hold the bolster and truck frame against substantial relative movement longitudinally of the truck, there is provided an anchor device including a bolt 14, received in a tube 15 which is shorter than the bolt and forms therewith an elongated arm, having at its ends flanges 16 welded to the tube at W and opposing upright transverse webs 17 on brackets 18 and 19 on the truck frame and bolster, respectively. A rubber pad 20 is placed between each flange 16 and the adjacent web 17 and preferably one or more shims 21 are used to effect desired spacing of the bolster and truck frame and desired precompression of the pad material.

25 A socket element 22 slidably engages the other face of each web 17 and seats a ball segment 23. Preferably one or more shims 24 are placed between ball segment 23 and the bolt head 14a.

30 Flange 16, pad 20 and ball segment 23 closely surround bolt 14 and move with it transversely of the normal axis X of bolt 14 when springs 13 deflect vertically or transversely of the truck or when the bolster moves transversely of the truck due to swing hanger action and the bolt shifts from the position shown in Figure 2 to a position shown in Figure 3. Socket pad 22, however, has a large central opening and is movable relative to bolt 14 transversely of axis X, as is indicated in Figure 3. Preferably pad 20 has an annular lip 25 filling the space between bolt 14 and the periphery of the opening therefor in web 17. The material of the lip may distort to accommodate inclination of bolt 14 from its normal position but maintains the bolt centered in the web aperture.

35 The arrangement described requires sliding movement of socket member 22 over the surface of web 17 whenever the arm is inclined from its normal position and the friction between socket pad 22 and web 17, together with the friction between socket member 22 and ball segment 23, will snub the relative movement of the bolster and truck frame transversely of the arm axis. Preferably the pad and ball and socket arrangement is duplicated at each end of the arm and nuts 26 on the other end of the bolt provide means for adjusting the pressure of pads 20 and 22 on the webs clamped between them.

40 To avoid undue wear in the parts sliding over each other, it is preferred to form such parts of different materials. For example, if the ball element 23 is of ferrous metal, the socket element 22 is preferably of material such as is generally used for lining brake drums or discs, one type of which is sold under the trade name "Thermoid." Other combinations of ferrous and non-ferrous materials may be used. The bearing element sliding over the truck part bracket should be of non-ferrous material for the best results.

45 Figure 4 illustrates another form of the invention corresponding in all respects to that previously described, except that the inter-engaging faces of the anchor socket pad 32 and the truck part web 27 are concavo-convex, instead of lying in a flat plane, as are the opposing faces of elements 22 and 17, and except that there are no lips on rubber pad 30 extending into the aperture in web 27. The pad and anchor bolt 24 are centered relative to the web aperture by an annular rib 38 on the web, seating the outer periphery of pad 30. This arrangement

avoids the compressive distortion of a rubber lip between the bolt and the web but increases the resistance to the movement of socket pad 32 over the bracket web 27 due to the greater pressure exerted by pad 30 as socket pad 32 rides up the inclined surface of the web.

Figure 5 illustrates another form of the invention corresponding generally to the arrangement shown in Figures 1, 2 and 3 except that a pad 49 of rubber-like material, and a backing flange 46, is positioned between the rear of the ball segment 43 and the bolt head 44a.

Figure 6 illustrates another form of the invention in which the single yielding pad 50, between the frame web 55 and the anchor flange 56, is bonded to steel plates 57, having flanges 58 and 59 respectively, to engage the aperture in web 55 and to surround the bolt 54, thus centering the anchoring device about the bracket web aperture.

Figure 2 shows a rubber pad 20 between each end of spacer tube 15 and the associated truck part flange 17 and a ball socket pad 22 and ball segment 23 on the other side of each truck part flange 17. This provides an anchor which is always rigid longitudinally in tension and rigid in other directions until precompression of rubber pads 20 is exceeded.

In Figure 5, if the same arrangement of rubber pad 40 between the spacer tube and the associated truck part flange and the same arrangement of ball and socket and rubber pad on other side of the associated flange is used at both ends of the anchor, the anchor will have the same longitudinal flexibility as the conventional anchor in both directions after precompression of pads 40 and 49 is exceeded.

Figure 7 shows an arrangement in which one end of the anchor is provided with a rubber pad 60 between spacer tube 61 and the associated truck part flange 62 and is provided with a ball seat 63 and ball segment 64 on the other side of the flange. This corresponds to the arrangement shown in Figure 2. The other end of the anchor is provided with a ball segment 65 and ball seat 66 between the spacer tube and associated truck part flange 67 and is provided with a rubber pad 68 on the outer side of the truck part flange 67. This provides an anchor arrangement which is half as flexible longitudinally in both directions as a conventional anchor after precompression of pads 60 and 68 is exceeded.

Each form of the invention includes the feature of providing snubbing action by energy dissipation during frictional sliding between elements of the anchor and elements of the truck frame and bolster to which the anchor is connected. This snubbing action results whether inclination of the anchor device is due to vertical oscillation or lateral deflection of the bolster springs or is due to both vertical oscillation and lateral deflection of the springs. This snubbing action eliminates the necessity of separate snubbing devices which have been generally utilized and frequently duplicated in the same truck to control vertical and lateral movements, respectively.

The snubbing action or frictional sliding action of the non-ferrous socket pads, relative to an associated part when the anchor moves to an inclined position due to either vertical oscillation or lateral deflection of the bolster springs or both, is cushioned by the rubber pad lip (Figures 1-3, 5, and 7) beginning when sliding action begins. When separate snubbers have been used previously, there has been no corresponding cushioning of the snubbing action.

Obviously trucks having anchor arrangements as disclosed above are less expensive than the conventional type which requires separate snubbing devices to control vertical oscillations and lateral deflections of the bolster springs.

It will be understood that the anchoring of the truck bolster to the truck frame is illustrative and that other parts, such as, for example, the bolster and the equalizers or the truck frame and journal boxes, may be an-

chored by similar devices and that anchors may be disposed transversely of the truck frame to limit relative lateral movement of main truck parts while accommodating their relatively vertical movement.

5 The details of the invention may be varied other than as shown without departing from the spirit of the invention and the exclusive use of those modifications coming within the scope of the claims is contemplated.

What is claimed is:

- 10 1. In a device for anchoring one railway truck part to another relatively movable truck part, an elongated arm, clamping structures at an end of said arm for connecting the device to a truck part, at least one of said structures including a member with a truck part-engaging face extending transversely of the arm and being substantially immovable transversely of the arm but constructed to accommodate inclination of the arm to said member, the other of said structures having a member with a truck part-engaging face extending transversely of the arm and being adapted normally to slide over the truck part and being movable transversely of the arm relative to the first-mentioned member when the arm is inclined to the truck part, at least one of the clamping structures includes a bearing for the truck part-engaging member comprising rigid ball and socket surfaces, one of said surfaces being of ferrous metal and the other of said surfaces being of non-ferrous material.
- 15 2. An anchoring device as described in claim 1 in which the first-mentioned member is of rubber-like material and the second-mentioned member is of non-ferrous material.
- 20 3. An anchor device for connecting relatively movable truck parts, comprising an elongated arm, and truck part clamping structures spaced apart at an end of the arm, one, clamping structure including a truck part opposing member formed of distortable rubber-like material and held against movement transversely of the arm, the associated clamping structure including members of non-distortable material normally slidable over each other transversely of the arm and at least one of which is movable transversely of the arm, the member of distortable material having its truck part-opposing face presented towards the adjacent end of the arm.
- 25 4. An anchor device as described in claim 3 in which another element of distortable material yieldingly holds the members of non-distortable material, which are slidable over each other, against movement towards the adjacent end of the arm.
- 30 5. An anchor device as described in claim 3 in which associated clamping structures are provided at each end of the arm and the member of distortable material in each pair of clamping structures has its truck part opposing face presented towards the adjacent end of the arm, and the members of non-distortable material in each pair of clamping structures are held against movement towards the adjacent end of the arm, whereby movement of the truck parts away from each other is prevented and movement towards each other is prevented up to the point where precompression of the distortable material is exceeded.
- 35 6. An anchor device as described in claim 3 in which associated clamping structures are provided at each end of the arm and the member of distortable material in each pair of clamping structures has its truck part opposing face presented towards the adjacent end of the arm, and at least one of the opposing clamping structures is provided with an element of distortable material yieldingly limiting the movement of the truck part engaging members towards the adjacent end of the arm, whereby movement of the truck parts towards and away from each other is prevented up to the point where precompression of the distortable material is exceeded.
- 40 7. An anchoring device as described in claim 3 in which the associated clamping structures are provided at each end of the arm and the member of distortable material in one of said structures has its truck part-opposing face presented towards the adjacent end of the arm, and the
- 45 8. An anchor device as described in claim 3 in which the associated clamping structures are provided at each end of the arm and the member of distortable material in each pair of clamping structures has its truck part opposing face presented towards the adjacent end of the arm, and the members of non-distortable material in each pair of clamping structures are held against movement towards the adjacent end of the arm, whereby movement of the truck parts away from each other is prevented and movement towards each other is prevented up to the point where precompression of the distortable material is exceeded.
- 50 9. An anchor device as described in claim 3 in which associated clamping structures are provided at each end of the arm and the member of distortable material in each pair of clamping structures has its truck part opposing face presented towards the adjacent end of the arm, and at least one of the opposing clamping structures is provided with an element of distortable material yieldingly limiting the movement of the truck part engaging members towards the adjacent end of the arm, whereby movement of the truck parts towards and away from each other is prevented up to the point where precompression of the distortable material is exceeded.
- 55 10. An anchor device as described in claim 3 in which the associated clamping structures are provided at each end of the arm and the member of distortable material in one of said structures has its truck part-opposing face presented towards the adjacent end of the arm, and the
- 60 11. An anchor device as described in claim 3 in which the associated clamping structures are provided at each end of the arm and the member of distortable material in each pair of clamping structures has its truck part opposing face presented towards the adjacent end of the arm, and the members of non-distortable material in each pair of clamping structures are held against movement towards the adjacent end of the arm, whereby movement of the truck parts away from each other is prevented and movement towards each other is prevented up to the point where precompression of the distortable material is exceeded.
- 65 12. An anchor device as described in claim 3 in which the associated clamping structures are provided at each end of the arm and the member of distortable material in each pair of clamping structures has its truck part opposing face presented towards the adjacent end of the arm, and at least one of the opposing clamping structures is provided with an element of distortable material yieldingly limiting the movement of the truck part engaging members towards the adjacent end of the arm, whereby movement of the truck parts towards and away from each other is prevented up to the point where precompression of the distortable material is exceeded.
- 70 13. An anchoring device as described in claim 3 in which the associated clamping structures are provided at each end of the arm and the member of distortable material in one of said structures has its truck part-opposing face presented towards the adjacent end of the arm, and the

member of distortable material in the structure at the other end of the arm has its truck part opposing face presented away from the adjacent end of the arm.

8. In combination in a railway truck having relatively movable main parts and an elongated anchor device with structures at its ends clamping said parts respectively and adapted to transmit thrust and pull lengthwise of the anchor device between the parts, the structure clamping at least one of the parts including a member in frictional slidable engagement with the associated truck part and movable bodily transverse of the axis of the anchor device when the latter is tilted by the relative movement of the truck parts transversely of said axis, at least one of the clamping structure members in sliding engagement with the truck part being of non-ferrous material, there being a bearing for the same seated on the elongated arm comprising ball and socket surfaces, one of said surfaces being of ferrous metal and the other of said surfaces being of non-ferrous material, and the other clamping structure being held against movement transversely of the axis of the anchor.

9. In combination in a railway truck having relatively movable main parts and an elongated anchor device with structures at its ends clamping said parts respectively and adapted to transmit thrust and pull lengthwise of the anchor device between the parts, the structure clamping at least one of the parts including a member in frictional slidable engagement with the associated truck part and movable bodily transversely of the axis of the anchor device when the latter is tilted by the relative movement of the truck parts transversely of said axis, the opposing faces of the truck part and the clamping structure member slidably engaging the same being in convex-concave relation.

10. An elongated anchor for connecting two railway vehicle truck parts which move relative to each other transversely of the longitudinal axis of the anchor comprising an elongated arm, clamping structures at an end

5 of the arm spaced apart lengthwise of said axis to receive a truck part between them, one of said clamping structures including a member centered on the arm and a truck part-engageable member slidable over the first mentioned member transversely of said axis when the arm axis is inclined from its normal position.

11. An anchor according to claim 10 in which the two members slidable over each other have concave-convex opposing faces.

10 12. An elongated anchor for connecting two railway vehicle truck parts which move relative to each other transversely of the longitudinal axis of the anchor comprising a rigid elongated arm, a pair of clamping structures at each end of the arm spaced apart lengthwise of said axis to receive a truck part between them, each one of said pairs of clamping structures including a member immovable lengthwise of the arm and relative to the other end of the arm and centered on the arm and a truck part-engageable member slidable over the first mentioned member transversely of said axis when the arm axis is inclined from its normal position.

15 13. An anchor according to claim 12 in which the two members slidable over each other have concave-convex opposing faces.
